UNITED STATES PATENT OFFICE.

LOUIS M. KREGELIUS, OF CLEVELAND, OHIO, ASSIGNOR TO THE UNITED STATES PLATERS SUPPLY COMPANY, OF CLEVELAND, OHIO, A CORPORATION OF OHIO.

METAL CONTAINER.

Application filed March 18, 1920. Serial No. 366,752.

To all whom it may concern:

Be it known that I, LOUIS M. KREGELIUS, a citizen of the United States, and a resident of Cleveland, county of Cuyahoga, and State 5 of Ohio, have invented a new and useful Improvement in Metal Containers, of which the following is a specification, the principle of the invention being herein explained and the best mode in which I have contemplated applying that principle, so as to distinguish it from other inventions.

The present improvement, relating, as indicated, to a metallic container, has more particular regard to a container of this sort 15 that will be adapted to preserve in airtight condition polishing compositions which require to be removed as a solid body when desired for use. Such compositions are usually placed in the container in a plastic condition, 20 and upon subsequently solidifying they sometimes expand slightly so that it becomes difficult to withdraw the cake of composition intact from the can.

The object of the invention, accordingly, 25 is to provide a container or can which may be conveniently opened without breaking or injuring the cake of material contained therein, and to the accomplishment of this object the invention, then, consists of the 30 means hereinafter fully described and particularly pointed out in the claims, the annexed drawing and the following description setting forth in detail certain mechanism embodying the invention, such disclosed 35 means constituting, however, but one of various mechanical forms in which the principle of the invention may be used.

In said annexed drawing:—

Fig. 1 is a central vertical section of my 40 improved container; Fig. 2 is a top plan view thereof; Fig. 3 is a transverse section taken on the plane indicated by the line 3—3, Fig. 1; and Fig. 4 is an enlarged sectional detail.

The body of the can, as best shown in 45 Figs. 1 and 3, consists simply of a plain cylinder formed by rolling up a rectangular metal sheet until its edges 2 and 3 overlap to form a longitudinal seam. Solder 4 is 50 then applied externally of the cylinder along the edge 2, so as to leave the inner overlapping edge 3 substantially entirely free. Accordingly, when the ends of the can are removed, as will be presently described, the 55 body 1 may be readily separated along the

line of such seam by simply inserting a sharp instrument, such as a knife or the like, between said overlapping edges 2 and 3, whereupon the line of solder 4 can be broken and such body sprung off or freed from the cake 60 of material contained therein, without injuring the latter.

The two ends 5 of the container are to all intents and purposes identical, each consisting of a dished plate having a lateral flange 65 6, the central depressed portion of the plate being adapted to fit snugly within the ends of such body 1, while the flange 6 projects therebeyond a slight distance, as clearly shown in Fig. 3. On one side such flange 6 70 is further extended to provide a laterally projecting ear 7 that may be seized, as by a pair of pincers, pliers or familiar keys, when it is desired to remove the corresponding end from the body. To seal the ends in place a 75 thin strip of solder 8 is applied in the exterior angle formed between the body 1 and such projecting flange 6, as best shown in Fig. 4. Such solder is, however, not heavy 80 enough to interfere with the breaking away of the cover in the fashion just described.

In use, the body of the can has the one end fitted and soldered in place, whereupon the can is filled and the other end applied and similarly soldered in place. When it is desired to remove the contents of the can, the same being in the form of a solid cake or stick as already indicated, one or both ends are removed and the body then slit along the line of the seam, whereupon such cake or 90 stick is left entirely free and may be readily removed.

Other modes of applying the principle of my invention may be employed instead of the one explained, change being made as 95 regards the mechanism herein disclosed, provided the means stated by any of the following claims or the equivalent of such stated means be employed.

I therefore particularly point out and distinctly claim as my invention:—

1. A wholly removable container for slowly solidifying material comprising removable end plates, a body portion formed of a cylinder of sheet metal, of greater height 105 than the diameter of said end plates joined to said end plates and providing an underlapped portion of substantial width, a sealing element applied to the outer edge of said cylinder along a line of the body of said 110

cylinder spaced from the other edge, said underlapped portion being free over the remaining area thereof, whereby cutting the outer ply will free the sheet material from 5 said contents.

2. A wholly removable container for slowly solidifying material comprising countersunk end plates, a body portion formed of a cylinder of sheet metal, of greater height 10 than the diameter of said end plates wrapped about the countersunk portions of said end plates and providing an underlapped portion of substantial width, a sealing element applied to the outer edge of said cylinder 15 along a line of the body of said cylinder

spaced from the other edge, said underlapped portion being free over the remaining area thereof, whereby cutting the outer ply will free the sheet material from said contents, the countersunk cover plates, for the 20 respective ends of the cylinder so formed, having projecting ears in vertical alignment so as to be each readily removable, preliminary to cutting the overlapped portion of the body of the container, to wholly remove 25 the same from said solidified material.

Signed by me this 15th day of March, 1920.

LOUIS M. KREGELIUS.
